United States Patent Office

Des. 199,021
Patented Sept. 1, 1964

199,021

WATER CLOSEST

Henry M. Stairs, Jr., Louisville, Ky., assignor to American Radiator & Standard Sanitary Corporation, New York, N.Y., a corporation of Delaware

Filed July 10, 1962, Ser. No. 70,866

Term of patent 14 years

(Cl. D4—5)

Fig. 1.

Fig. 2.

FIG. 1 is a perspective view of a water closet, showing my new design; and

FIG. 2 is a side elevational view thereof.

The rear of the tank is flat and plain.

I claim:

The ornamental design for a water closet, substantially as shown and described.
